UNITED STATES PATENT OFFICE.

JOEL S. GRINDEE, OF SEATTLE, WASHINGTON.

WIND-DEFLECTOR SHIELD.

Application filed January 28, 1924. Serial No. 688,964.

To all whom it may concern:

Be it known that I, JOEL S. GRINDEE, a citizen of the United States, residing at Seattle, in the county of King and State of Washington, have invented a new and useful 5 Wind-Deflector Shield, of which the following is a specification.

My invention relates to wind deflector shields and more particularly to a shield that 10 is adapted for installation and use in connection with dirigible mooring towers or masts. The principal objects of the invention are to provide a shield, in combination with a mast or tower, that is arranged to 15 revolve around said mast with the direction of the wind and to deflect the wind from the forward end of a dirigible, zeppelin or other lighter-than-air-craft moored thereto, thus serving to protect said air craft from 20 damage during windy weather. Other objects are to provide a shield which is simple and durable in construction, reliable and efficient in operation, and which may be manufactured at a comparatively small cost.

With the above and other objects in view 25 which will appear as the description proceeds, the invention consists of the novel construction, adaptation, arrangement and combination of parts hereinafter described 30 and claimed. These objects are accomplished by devices illustrated in the accompanying drawings, wherein:—

Figure 1 is a view in side elevation showing the device installed on a mooring tower 35 and an air craft secured thereto;

Fig. 2 is a view in side elevation of the shield and showing portions of the tower and air craft;

Fig. 3 is a view in front elevation of the 40 same;

Fig. 4 is a view in longitudinal vertical section taken substantially on a broken line 4, 4 of Fig. 3; and

Fig. 5 is a view in transverse vertical 45 section taken on a broken line 5, 5 of Fig. 4.

Referring more particularly to the drawings throughout which like reference numerals designate like parts, the numeral 5 indicates a mooring tower having a mast 6 50 mounted on its upper platform. The shield, designated as a whole by the numeral 7, is centrally provided with a mooring pin 8 whose outer end is secured to said mast by a ball bearing connection or other anti-friction device as shown at 9 in Fig. 4.

The skin or covering 10 of the shield 7

is preferably made of relatively thin sheet metal formed in the shape of a concaved cone, although the device is not limited to this particular shape or details of construction. Segmental vanes 11 are radially arranged in spaced apart relation to fit the exterior contour of the skin 10 and are together secured to the mooring pin 8 by 60 screws or other suitable fastenings shown at 12 in the drawings.

Strengthening ribs 13 are arranged on the inside of the skin 10 directly under each of the vanes 11 and are secured through said skin to said vanes by screws or the like. The 70 inner or converging ends of said ribs are separated from said skin and are fastened to a transverse plate 14 secured around the mooring pin 8 and to the interior surface of said skin for the purpose of reinforcing 75 the forward end of said shield as clearly shown in Fig. 4 of the drawings. The inner end of the pin 8 is provided with an eye 15 to which the dirigible or other air craft, designated by the numeral 16, is made fast 80 by means of a cable 17 or other suitable mooring.

The shield 7 is provided with an opening 85 through the skin 10 designated by the numeral 18 and steps 19 mounted on said shield within said opening are arranged so that passengers may readily go on board the air craft from the upper platform of the tower 5. An annular track 20 is mounted on said 90 platform concentric with the mast 6 and rollers 21 secured to said shield substantially at its center of gravity are arranged to engage said track for reasons presently set forth.

In the operation of my wind deflector 95 shield, assuming that a dirigible is secured thereto as shown in the drawings, the wind blowing from the forward end will strike the apex of the cone, and, with the assistance of the vanes 11, the longitudinal or horizontal axis of the shield 7 will assume the direction from which the wind is blowing. The shield is light in weight compared with its surface area and any shifting of the wind will cause said shield to turn there-with horizontally around the mast 6 by reason of the ball bearing connection 9 and with its weight carried by the ball bearing rollers 21 and track 20, thus causing said shield to revolvably retain its alignment 100 with the direction of the wind at all times as will be readily understood.

It will be obvious that the wind will be deflected outwardly all around the shield by reason of its conical shape which is concaved for the purpose of increasing the outward deflection. The increased air pressure immediately around the larger end of the shield as the wind leaves same will in itself serve to continue the deflection of the wind for which reason the diameter of said shield may be smaller than the greatest diameter of the dirigible. The diameter of the shield is made sufficient to deflect the wind from impinging on any part of the dirigible forward of its greatest diameter and at the same time so that the wind will again assume its horizontal direction at the point of the dirigible's greatest diameter, thus causing same to ride easily in a suspended horizontal position and serving as a protection against damage or danger of being blown away during stormy weather.

Having thus described my invention what I claim is:—

1. The combination with a dirigible mooring mast of a wind deflector shield comprising a divergent body, anti-friction connecting means for the smaller end of said shield whereby same may revolve around said mast, vanes for said shield, track means for supporting said shield, and passage means carried by said shield substantially as specified.

2. The combination with a dirigible mooring mast of a wind deflector shield comprising a concave conical body, segmental vanes on said body, a mooring pin in the smaller end of said body, pivotal means connecting said shield and mast, annular track means adapted to carry said shield, and passage means carried by said shield substantially as specified.

JOEL S. GRINDEE.
